UNITED STATES PATENT OFFICE.

NELLIE SSELLS, OF COLUMBUS, OHIO.

DESIGN FOR A TOY.

51,610.

Specification for Design.

Patented Dec. 18, 1917.

Application filed October 29, 1917. Serial No. 199,197. Term of patent 3½ years.

To all whom it may concern:

Be it known that I, NELLIE SSELLS, a citizen of the United States, residing at Columbus, in the county of Franklin and State of Ohio, have invented a new, original, and ornamental Design for a Toy, of which the following is a specification, reference being had to the accompanying drawing, forming part thereof.

The figure is a perspective view of a toy, showing my new design.

I claim:

The ornamental design for a toy, as shown.

NELLIE SSELLS.

Witness:

W. S. McDOWELL.
